(57) **CLAIM**

The ornamental design of the airline tray cover, as shown and described.

DESCRIPTION

FIG. 1 is a perspective view of the airline tray cover, showing my new design.

FIG. 2 is a top view thereof.

FIG. 3 is a bottom view thereof; and,

FIG. 4 is a perspective view showing the airline tray cover in an environmental use.

The broken lines shown in the drawings represent unclaimed portions of the design and form no part thereof.
